UNITED STATES PATENT OFFICE.

IVER JOHNSON AND MARTIN BYE, OF WORCESTER, MASSACHUSETTS.

BREECH-LOADING FIRE-ARM.

SPECIFICATION forming part of Letters Patent No. 253,292, dated February 7, 1882.

Application filed September 4, 1880. (No model.)

To all whom it may concern:

Be it known that we, IVER JOHNSON and MARTIN BYE, both of Worcester, in the county of Worcester and State of Massachusetts, have 5 invented certain new and useful Improvements in Fire-Arms, of which the following is a specification.

Our invention relates to improvements in breech-loading fire-arms; and it consists in the 10 construction of the fore stock and the manner of attaching the locking devices thereto; in connecting the breech-piece and lock-plate by means of the side plates which support the hammers, the rear projection on the lock-plate, 15 and the tang of the breech-piece; in the novel manner of arranging and adjusting the main-spring to retract the hammer from the nipple, of operating the cartridge-extractor while the barrels are being turned for loading, and of 20 connecting the hammer and tumbler and mounting them on the lock-plate.

In the accompanying drawings, which illustrate a breech-loading gun showing all our improvements as embodied in the best way now 25 known to us, Figure 1 is a lengthwise vertical section. Fig. 2 is a side elevation, partly in section. Figs. 3 and 4 are perspective views of the two parts which alone form the front stock. Fig. 5 is a sectional view of the lock. 30 Fig. 6 is a section on line $x-x$, Fig. 5. Fig. 7 is a perspective view of the hammer and tumbler. The lower shoulder of the recess in the tumbler projects beyond the upper shoulder of 35 that recess, as shown more clearly in Fig. 5. Fig. 8 is a perspective view of the breech-piece, and Fig. 9 is a similar view of the lock-plate.

The barrels A turn on the pin G in the breech-piece D in the usual way, and are provided with the usual projecting blocks, a a' a^2 —the block 40 a for connecting the front stock, B, to the barrels, the block a' for connecting the barrels to the breech-piece D, and the block a^2 for connecting them with the usual locking-bolt.

One feature of our invention consists in 45 constructing the front stock, B, of the metal piece b and the wooden piece b' only, and in mounting the locking-lever b² and its spring b³ in a hollow projection on the metal piece b and snugly fitting this metal piece b to the wooden 50 part b' of the front stock. The hollow projection on the metal piece b extends through a

mortise in the wooden piece b' and terminates flush with the exterior surface thereof. The lever b² fills and conceals the open side of the hollow projection on the metal piece b, and renders unnecessary the outside plate for holding or guiding the locking-lever heretofore employed.

Another feature of our invention consists in the construction of the breech-piece D and lock-plate d and in the manner of connecting them together. The breech-piece D has the usual 60 slots to receive the blocks a' a² and the locking-bolt a³, is grooved underneath to receive the fore part of the lock-plate d, and has its 65 rear end shaped to receive the projection d² thereon. It is also provided with a tang extending back between the upper parts of the projections d² to a projecting piece on the rear end of the lock-plate d. This tang is fastened 70 to this projecting piece and to the projections d² by screws. The free part of the lock-plate d is also fastened to the piece D by a screw, thus firmly uniting the parts D and d together, which two parts so united form a strong 75 breech-piece, to which the rear stock is secured by a screw-bolt extending from the shoulder-rest to the projecting piece on the lock-plate d, into which it is screwed. A leaf-spring, d³, 80 which acts on the locking-bolt a³, is used instead of the usual spring acting on the finger-lever of the top snap, is attached to the piece D, and lies in a recess therein, which recess is covered by the lock-plate d.

Another feature of our invention consists in 85 the novel arrangement of the mainspring and tumbler by which the hammer is retracted from and held off of the nipple, and consists in placing the ends of both leaves of a double-leafed mainspring, f, in a recess on the tumbler F, 90 which is controlled by the usual sear, f', and sear-spring f². The other end of the mainspring f fits in a seat in the projecting piece on the lock-plate d. The upper leaf of the mainspring f bears on the upper shoulder of the recess in 95 the tumbler F, while the lower leaf rests on top of a set-screw, f³, by which it can be adjusted to throw back and hold the hammer at quarter or half cock, or in any other position, provided it be not so far as to prevent the requisite action of the upper leaf. The actions of the two leaves are secured by the difference of leverage 100

with which they act on the tumbler, and this difference of leverage arises from the length of the upper shoulder of the recess and the distance through which it moves (as it describes an arc of smaller radius) being less than the length and movement of the lower shoulder, as clearly indicated in Fig. 5, from which it will readily be seen that in cocking the gun the upper leaf is depressed by the upper shoulder of short leverage and small movement, while the lower leaf remains on the end of the set-screw. By releasing the tumbler the reaction of the upper leaf will throw the hammer forward, and it will strike the nipple or firing-pin if the lower leaf be properly adjusted by the set-screw f^3 ; but during the fall of the hammer and at a time before it strikes the nipple, determined by the adjustment of the lower leaf, the longer and farther moving lower shoulder of the recess strikes the lower leaf of the mainspring, which it carries away from the set-screw, and both leaves are now exerting substantially the same force on each shoulder; but on account of the greater leverage the lower leaf is enabled to overcome the resistance of the upper leaf and to bring back the hammer to quarter or half cock, or to a position determined by the adjustment of the set-screw. When the locking-bolt is drawn back and the barrels turned on pin G (in the usual manner) the end of the cartridge-extractor arm g' comes against the shoulder g^2 , and the extractor g is thus moved out from the open breech of the barrels in the usual manner; but this shoulder g^2 is on a metal piece, g^4 , which is mounted on a spring, g^5 , as shown in the drawings, and which has a second shoulder, g^3 , forming a continuation of the metal piece g^4 and extending above the shoulder g^2 , the whole fitting in a recess in the front end of the stationary breech-piece D, and held out by the spring g^5 when the gun is closed, so that the shoulder g^2 is in the arc described by the arm g' in opening the gun, and in which arc it remains until pushed down by the barrels striking and acting on the shoulder g^3 , which is pressed upon by the rib or the metal between the barrels, so as to carry shoulder g^2 down below the level of extractor-arm g' , and thereby leave that arm free to move while the gun is open. This arrangement of the extractor whereby it is left free to be pushed back when the gun is open—that is, ready to receive a new cartridge—constitutes another feature of our invention.

55 The hammer F' and tumbler F are rigidly connected by the piece f^4 , and both are supported on the projections d^2 by a pin, f^5 . Connecting the hammer and tumbler rigidly in this way by a connecting-piece extending from

the tumbler and at one side of the journal 60 which supports them, so as to leave room between the hammer and tumbler for that part of the lock-plate through which the journal of the hammer and tumbler passes, also constitutes a feature of our invention. 65

What we claim as our invention is—

1. The front stock, B, composed of the metal piece b and the wood stock b' , the metal piece b having a hollow projection formed on it, which extends through a mortise in and terminates 70 flush with the exterior surface of the wood stock b' , and having the locking-lever b^2 and its spring b^3 mounted in this hollow projection, substantially as set forth.

2. A breech-piece for fire-arms, consisting of 75 the breech-piece D and a lock-plate, d, having projections d^2 for supporting the hammer and tumbler, and a projecting piece on its rear end, the tang of the breech-piece D passing between the projections d^2 , to which and the projecting piece it is fastened, substantially as and for the purposes set forth.

3. The combination of the hammer having a tumbler provided with a recess the upper shoulder of which is shorter and nearer the 85 center of motion than the lower shoulder thereof, with a double-leaved mainspring, both leaves of which lie in the recess in the tumbler, the upper leaf bearing against the upper shoulder and the lower leaf resting on a set-screw, by 90 turning which it can be raised or lowered to the proper position to catch the lower shoulder while the hammer is falling, so as to throw the hammer back after it has struck, substantially as set forth. 95

4. The combination of the cartridge-extract- 100 or g and its arm g' with the metal piece g^4 , mounted in a recess in the breech-piece D and held out by the spring g^5 , so that its shoulder g^2 is in the arc described by the end of the 105 arm g' in opening the gun, and its shoulder g^3 is struck and depressed by the barrels of the gun, so as to cause the shoulder g^2 to move away from the arm g' and leave it free to be pushed in when the gun is open, substantially as set forth.

5. The hammer and tumbler rigidly connected by a connecting-piece, f^4 , lying at one side of the pin f^5 , which supports the hammer and tumbler, in combination with the projection d^2 , lying between the hammer and tumbler, substantially as described. 110
